Int. Cl. D26—03

The figure is a front perspective view of a lighting casing showing my new design.

The top, back, and undisclosed side of the casing shown in the figure are plain except for the ridge-and-recess design.

The broken line showing is for illustrative purposes only.

This application is a division of my copending application Ser. No. D9,331, filed Nov. 8, 1967.

I claim:

The ornamental design for a lighting casing, as shown and described.
